(57) **CLAIM**

The ornamental design for a tailpipe for a vehicle, as shown and described.

DESCRIPTION

This application is related to the following co-pending application: application Ser. No. 29/306,764, entitled “Tailpipe for a Vehicle”.

FIG. 1 is a left, front, elevated perspective view of a tailpipe for a vehicle according to my novel design;

FIG. 2 is a front view thereof;

FIG. 3 is a top view thereof;

FIG. 4 is a bottom view thereof;

FIG. 5 is a left side view thereof; and,

FIG. 6 is a right side view thereof.

The broken lines are for illustrative purposes only and form no part of the claimed design.

The broken line showing of a pattern of radiating fins in FIGS. 1 and 2 various portions of the exhaust tip in FIGS. 1-6 is included for the purpose of illustrating environment and forms no part of the claimed designs.
